UNITED STATES PATENT OFFICE

2,065,490

VIBRATION DAMPER

Harold H. Febrey, South Orange, N. J., assignor
to The American Steel and Wire Company of
New Jersey, a corporation of New Jersey

Application October 2, 1934, Serial No. 746,611

4 Claims. (Cl. 173—13)

This invention is a vibration damper for a strand having a free metal surface. Such a strand may be an electric power transmission cable or a rail bond, neither of which ordinarily carries an insulating cover. The damper is particularly intended to damp high-frequency vibrations.

The damper is illustrated by the accompanying drawing, in which:

10 Figure 1 is a top view of the damper.

Figure 2 is a side view.

Figure 3 is a top view showing the damper in use.

15 Figure 4 is a side view showing the damper in use.

More specifically, this damper includes a spring metal rod 1 that is bent to include two respectively offset substantially parallel portions 1^a and 1^b interconnected by a right angular portion 1^c and having right angular end portions 1^d, and three metal shoes 2 in the form of channels having right angular loops 2^a on their outer sides through which the right angular portions 1^c and 1^d of the rod are passed so that these channels 20 are interconnected in substantially axial alignment. The portions 1^a and 1^b are of unequal lengths so that the shoes 2 are unequally spaced.

25 Figures 3 and 4 show the damper in use, the portions 1^a and 1^b being flexed beside the strand 3 of a rail bond and the shoes being engaged with the latter alternately on opposite sides of the same. The portions 1^a and 1^b are in the form of curved sections which are normally free of the strand 3. It is to be noted that the shoes 2 provide free metal surfaces which directly engage the strand, these shoes being separated fixed distances by the flexible rod 1 which interconnects them and being also resiliently pressed against the strand by this rod. The pressure applied to the shoes is not sufficient to cause material distortion of the strand.

30 The direct metallic contact is of advantage in that it is particularly effective in damping high-frequency vibrations, which might be passed if there were rubber or other soft material between the shoes and the strand. The pivotal mounting of the shoes 2 is of advantage in that it permits them to adapt themselves to the longitudinal curvature of the strand 3. Although this is illustrated as being straight, it often assumes a curved shape at one or more points, particularly in the case of long rail bonds which are not tensioned. The separation of the shoes 2 at unequal distances is an advantage in that the damper is then effective regardless of the wave length or period of the vibration in the strand 3. If the shoes are evenly spaced there is some chance that their spacing may coincide with the wave length or pe-

riod of the vibration in the strand 3 so that they might not be particularly effective in damping such a vibration.

Although a specific example of the invention is illustrated in accordance with the patent statutes, 5 it is not intended to thereby limit its scope, except as defined by the following claims.

I claim:

1. A vibration damper including at least three strand-contacting shoes and means for interconnecting said shoes in tandem with at least two adjacent spaces between shoes unequal and for resiliently pressing said shoes against a strand to be damped.

10 2. A vibration damper including at least three metal shoes each integrally providing a metal strand-contacting surface and means for interconnecting said shoes with said surfaces in spaced tandem relationship and for resiliently pressing said surfaces against a strand to be damped, said means fixedly separating the shoes in position with at least two adjacent distances between strand contacting surfaces unequal.

15 3. A vibration damper including a spring metal rod that is bent to include two substantially parallel portions which are offset in respect to each other and are connected together by a portion extending at right angles to said parallel portions, each of said parallel portions having an end portion extending parallel to said connecting portion, each of said end portions and said connecting portion having a shoe in the form of a channel with a loop on its outer side for receiving its respective portion to pivot the shoe thereto, said shoes being so positioned as to bring 20 the channels in alignment with each other, said end portions and said connecting portion being of sufficient lengths to permit said shoes to pivot free from said parallel portions.

25 4. A vibration damper including a spring metal rod that is bent to include two substantially parallel portions which are offset in respect to each other and are connected together by a portion extending at right angles to said parallel portions, each of said parallel portions having an end 30 portion extending parallel to said connecting portion, each of said end portions and said connecting portion having a shoe in the form of a channel with a loop on its outer side for receiving its respective portion to pivot the shoe there- 35 to, said shoes being so positioned as to bring the channels in alignment with each other, said end portions and said connecting portion being of sufficient lengths to permit said shoes to pivot free from said parallel portions, said two sub- 40 stantially parallel portions which are offset in 45 respect to each other being of unequal lengths.

HAROLD H. FEBREY.
